PHONOGRAPH

John E. Renholdt, Bridgeport, Conn., assignor to
 Dictaphone Corporation, New York, N. Y., a
 corporation of New York

Application March 8, 1935, Serial No. 9,994

11 Claims. (Cl. 274—17)

This invention relates to phonographs of the commercial type and more particularly to improvements in the record-cylinder ejecting and switch-operating mechanisms therefor.

5 One of the objects of the invention is to provide more efficient mechanism for removing a record-cylinder from its support. Another object is to provide simple and practical switch-actuating mechanism associated with the record-cylinder ejecting mechanism.

10 Other objects are in part obvious and in part pointed out hereinafter.

15 The invention accordingly consists in the features of construction, combinations of elements, and arrangements of parts as will be exemplified in the structure to be hereinafter described and the scope of the application of which will be indicated in the following claims.

In the accompanying drawings, in which is 20 shown one of the possible embodiments of my invention:

Fig. 1 is a front elevation of a transcribing phonograph embodying the present invention;

Fig. 2 is a cross-section taken on line 2—2 of 25 Fig. 1;

Fig. 3 is a bottom plan of a portion of the base-plate of the machine showing the ejector and switching mechanisms under one set of conditions;

30 Fig. 4 is a similar view showing the same parts differently conditioned;

Fig. 5 is a fragmentary view similar to Figs. 3 and 4 but showing the ejector mechanism as in Fig. 3 and the switch mechanism as in Fig. 4;

35 Fig. 6 is a partial cross-section on line 6—6 of Fig. 2; and

Fig. 7 is a graphic illustration of the functional relationship of certain elements of the ejector mechanism.

40 Similar reference characters refer to similar parts throughout the several views of the drawings.

In the operation of transcribing phonographs of the cylinder type, it has been found that at 45 the end of a transcription the operator mechanically actuates the record-ejector to loosen the cylinder from the mandrel, even though the cylinder may not be immediately completely removed therefrom. In an earlier application a construction was shown whereby advantage was 50 taken of this mechanical action to cause operation of the motor circuit switch to its open position, thus insuring non-operation of the motor for so long as the ejector stood in its "out" or 55 protracted position. Thus, ordinarily the mo-

tor would be idle whenever the mandrel did not support a record-cylinder. Furthermore, means were provided for automatically closing the motor switch whenever a record-cylinder was brought into operative relation with the mandrel; or whenever the record-ejector was returned to its retracted position by any other act of the operator. These and other novel features are incorporated in the structure now to be described.

5 Referring to the drawings, it will be seen that the present phonograph comprises a base-plate 10, a pair of standards 11, and a housing 12. The housing 12 provides bearing support for a mandrel shaft 13 provided at one end with a 15 mandrel 14 which is adapted to support and frictionally engage a record-cylinder 15. The mandrel shaft also supports a loose pulley 16 which may be brought into driving connection with the said shaft by means of a clutch device 20 17 manually controlled in a known manner. The pulley 16 is connected by means of a belt 18 with an electric motor 19, suspended in a known manner from the underside of the base-plate 10.

25 A sound-box carriage 20 is supported for longitudinal movement relatively to the record-support 14 upon a pair of guide rods 21 and 22 extending between the standards 11. The carriage is propelled along the guide rods by means 30 of a feed-screw 23 driven from the mandrel shaft 13 through any suitable train of gears (not shown) disposed within the housing. A feed-nut 24 mounted on the carriage cooperates with the feed-screw.

35 The ejector device for freeing the cylinder from the mandrel is substantially like that shown in United States Patent No. 1,687,375, and comprises a plunger 25 supported in the housing 12 to move longitudinally of the machine. The operating end of the plunger 25 has a head 26 so shaped as to pass by the mandrel flange 27 but to engage the inner end of the record-cylinder 15 when the plunger is protracted from its inner or unoperated position. 45 The other end of the plunger is fastened to the upstanding arm 28 forming part of a longitudinally disposed link 29 which is supported beneath the base 10 and terminates at a point adjacent the outer end of the mandrel.

50 Here the link is pivotally connected at 30 to a lever 31, fulcrumed at 32 upon a shouldered screw, positioned rearwardly of the righthand end of an arcuate slot 33, itself located near the right front corner of the base 10. The free end 55

of lever 31 carries a roller 34 mounted on a screw 35. An actuating lever 36 is pivoted near the rear of the base 10 upon a screw 37, and at its forward end is provided with an upwardly extending portion 38 forming a fingerpiece for operating the lever. This fingerpiece extends through the said arcuate slot 33 to the upper side of the base 10. At a suitable point between the ends of lever 36 a stud 39 forms a pivotal 5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 498

mounting adjacent the apex 40 of a triangular lever 41, whose base 42 at one side of center has rolling contact with a roller 43 mounted upon a fixed stud 44, and at the other side of center has rolling contact with the aforesaid roller 34 positioned at the end of lever 31. The said lever 41 thus acts upon the roller 34 as a shiftable cam movable not only with respect to lever 31 but also relatively to actuating lever 36. A spring 45 having one end secured to lever 31 and the other end to cam lever 41 tends to hold the ejector parts in the unoperated position shown in Fig. 3. It will be seen by a comparison of the positions of the parts in Figs. 3 and 4 that as the lever 36 moves from its unoperated position in Fig. 3 to its operated position in Fig. 4, the cam lever 41 rocking about the pivot 39 is caused to oscillate also about the fixed fulcrum point 43 which is made continuously to approach nearer and nearer the center of the base 42 of the cam lever. At the same time the point of contact of the roller 34 with the base of the cam lever is moved continuously farther and farther away from the center of the triangular base while the lever 31 is being swung in a counterclockwise direction (referring to Figs. 3 and 4) about its pivot 32.

The operation in general will be largely obvious for it is evident that as the fingerpiece 38 is moved from left to right in slot 33 the ejector head will first be brought into contact with the inner end of the record-cylinder and thereafter will move the cylinder to the right, along the mandrel to the point where the cylinder may easily be removed by the fingers of the operator, this general aspect of the operation being no different from that of the ejector disclosed in Patent No. 1,687,375. However, during the operation of the ejector by the present lever system, the force applied manually at the fingerpiece is more advantageously utilized. It is a well known fact that record-cylinders have, because of temperature variations, a tendency to become tightly set upon the mandrel, so that a relatively great initial force must be applied to start the removal of the cylinder from the mandrel. Under such conditions a fixed leverage system for applying force to load is disadvantageous because there is relatively little resistance offered by the record to the force applied at the fingerpiece, after the record starts to move. Consequently the ejector is thrown violently through the remainder of its stroke at an ever-increasing rate of speed. Meanwhile the record-cylinder gains such a high velocity of movement that it is sometimes difficult to prevent its being thrown clear off the mandrel and thus broken, or at least considerably damaged.

This disadvantage is largely overcome in the use of an ejector lever system made in accordance with the principles of the present invention, and other positive advantages are gained, as for example, a substantial reduction in the throw of the fingerpiece relative to the throw of the ejector head. Fig. 7 shows the curve of ejector operation, the abscissa representing uniform increments of distance covered by the fin-

gerpiece and the ordinates the corresponding distances through which the ejector head moves. It will be seen that the increments of distance gained by the ejector head are not uniform but increase progressively from beginning to end of the throw. From these facts may be postulated an ever-increasing tendency to offset the above mentioned tendency of the fingerpiece continuously to gain velocity, whereby the speed of record-ejection is held under control.

In the earlier application mentioned above, means was shown connecting the ejector-actuating mechanism with the phonograph motor switch for controlling the operation of the motor in response to actuation of the ejector. In the present application is shown improved mechanism for this purpose and for permitting operation of the motor switch independently of the operation of the ejector when the latter stands in its "in" or unoperated position. The motor controlling switch 50, of known construction, is supported by a bracket having a downwardly depending arm 51 for supporting the switch and a horizontal base portion 52 which is secured to the underside of the base-plate 10 by means of 25 screws 53. The bracket has also a horizontal portion 54 offset downwardly from the portion 52 and connected therewith by means of a vertical portion 55. Rotatively mounted upon bracket member 54 by means of a stud 56 is an irregularly shaped lever 57, see Figs. 3 and 4, having at one end a laterally extending arm 58 and at the other end a downwardly extending finger 59. The switch 50 has a reciprocative plunger 60, secured by means of a cotter pin 61 to a toggle 35 link, 62, adjacent an end of said link. Link 62 is pivotally mounted by means of a stud 63 upon the irregular lever 57, as will be understood by reference to Fig. 3 or 4. The end of toggle link 62 is tapered to a high point at 64, the tapering 40 sides being adapted to contact a roller 65 pinned on the underside of lever 57. The toggle link has a slot connection with cotter pin 61 and also with screw 63, so is permitted limited endwise movement relatively to lever 57. A spring 66 extending between a pin 67 on lever 57 and a pin 68 on link 62 tends to hold one or the other of the tapered surfaces at the end of the link in contact with the roller 65. Lateral displacement of link 62 is limited by a pair of spaced abutments 69 and 70 which are formed upon and extend downwardly from bracket member 52. It will be clear from the description, thus far, that the switch plunger is snapped from its inner contact position to its outer open position or vice versa whenever the lever 57 is rocked about its pivot 56.

Pivoted to the lever 57 by means of screw 71 substantially in alignment with the laterally extending arm 58 and extending in the opposite direction from said arm is a finger 72 having an upward turned camming lug 73 at its outer end. This finger is normally held in its aligned relation with arm 58 by means of an abutment 74 extending downwardly from arm 58, and a spring 75 secured at one end to a pin 76 on finger 72 and at its other end to a pin 77 on lever 57. Thus the finger 72 is free to move against the reaction of spring 75 in a counter-clockwise direction, as seen in Figs. 3 and 4, but is prevented 70 from swinging in a clockwise direction by the abutment 74.

Referring to Figs. 1 and 2, there will be seen a finger lever 78 pivoted as at 79 to a bracket 80 depending from the underside of phonograph 75

base 10. The lever passes through a slot in the base and at its lower end is secured to the downwardly extending finger 59 of lever 57 by means of a pin 81. Thus it will be seen that under 5 certain conditions, referred to later, the lever 57 may be oscillated and the phonograph switch operated in either direction by means of the finger lever 78.

In the usual operation of the phonograph it 10 is intended, however, that the operation of the motor shall be controlled by the operation of the record-ejector. For this purpose a plate 85 is secured to the underside of ejector link 29 by means of screws 85'. Depending from this plate 15 is an angular camming member 86 adapted, under the set conditions illustrated in Fig. 3, which shows the ejector mechanism in its unoperated condition and the motor switch in contact closed position (contacts not shown), to engage a surface 87 on lever arm 58 while the 20 ejector parts are being moved to the operated position shown in Fig. 4. This engagement swings the lever 57 to the position shown in Fig. 4 and changes the switch to open-circuit 25 condition. Thus ejection of a record-cylinder breaks the phonograph motor circuit and puts the machine out of operation. The ejector parts are then held resiliently in operated position against the reaction of spring 45 until they are 30 returned to unoperated position either by returning the actuating lever 36 by means of the fingerpiece 38 to its position at the left end of slot 33, or by fully seating a new record-cylinder upon the mandrel. The holding means for the 35 ejector mechanism comprises a detent lever 88 pivoted upon link 29 and normally held in the position shown in Figs. 3 and 4 by means of a spring 89. A pin 90 projecting downwardly from the base 10 is engaged by the rounded end 40 of this lever when the ejector is in operated position (Fig. 4). As the spring 89 prevents movement of the lever the ejector parts are held immovable against the action of spring 45.

A pin 91 extending down from the plate 85 45 is adapted to cooperate with the upturned lug 73 on finger 72, to swing lever 57 clockwise and return the switch to closed-contact condition when the ejector link 29 is returned to its unoperated position, as in Fig. 3; but before any 50 movement may be imparted to lever 57 the surface 92 at the extreme end of lever arm 58 must ride off of the cam member 86; for as long as cam member 86 underlies the surface 92 the switch mechanism cannot be operated. 55 Thus the manual switch control 78 is rendered inoperative so long as the ejector stands in its "out" position.

However, when the parts are conditioned as in 60 Fig. 3, that is, when the ejector is "in", the motor circuit may be made and broken by operation of finger lever 78, since nothing interferes with free oscillation of lever 57. In Fig. 5 the ejector link is shown in unoperated position and the switch lever 57 in switch cut-off position.

With the parts as shown in Fig. 5 it is still 65 possible to work the ejector, for though moving the ejector link to the right brings the pin 91 into engagement with lug 73, further movement of the ejector is not prevented, since the pin 91 70 swings the finger 72 away from the abutment 74. The lug 73 then trips off of the pin 91 and, when the ejector has been fully operated, the parts 75 occupy the positions shown in Fig. 4 with movement of lever 57 blocked by cam member 86.

It is then impossible to again start the motor by operation of the manual control lever 78.

It will be seen that there is provided a construction of an essentially practical nature in which the several objects of this invention are 5 attained.

As many possible embodiments may be made of the above invention without departing from the scope thereof, it is to be understood that all matter herein set forth or shown in the accompanying drawings is to be interpreted as illustrative and not in a limiting sense.

I claim:

1. In a phonograph, in combination, a frame, a record mandrel mounted on the frame, a record-engaging plunger mounted on the frame, a link mounted on the frame and engaging the said plunger, an actuating lever pivoted to the frame, and means operatively connecting said actuating lever with said link comprising means for transmitting relatively great force to the link when the ejector stands at its "in" position and progressively to lessen the force transmitted to said link as the ejector moves toward its "out" position. 25

2. In a phonograph, in combination, a frame, a record mandrel mounted on the frame, a record-engaging plunger mounted on the frame, a link mounted on the frame and engaging the said plunger, an actuating lever pivoted to the 30 frame, and means operatively connecting said actuating lever with said link comprising means for moving the plunger progressively through increasing increments of travel in response to uniform movement of said actuating lever. 35

3. In a phonograph, in combination, a frame, a record mandrel mounted on the frame, a record-engaging plunger mounted on the frame, a link mounted on the frame and engaging the said plunger, an actuating lever pivoted to the 40 frame, and means operatively connecting said actuating lever with said link comprising means for moving the plunger at a continuously retarded velocity as the actuating lever is moved at a uniform rate. 45

4. In a phonograph, in combination, a frame, a record mandrel mounted on the frame, a record-engaging plunger mounted on the frame, a link mounted on the frame and engaging the said plunger, an actuating lever pivoted to the 50 frame, and means operatively connecting said actuating lever with said link comprising a lever pivotally connected with said link and camming means interposed between said link-connected lever and said actuating lever. 55

5. In a phonograph, in combination, a frame, a record mandrel mounted on the frame, a record-engaging plunger mounted on the frame, a link mounted on the frame and engaging the said plunger, an actuating lever pivoted to the 60 frame, and means operatively connecting said actuating lever with said link comprising a lever pivotally connected with said link and a shiftable rocker arm mounted on said actuating lever and having a camming surface in movable engagement with said link-connected lever and with a fixed abutment on said frame. 65

6. In a phonograph, in combination, a record-support, a motor for driving said support, a circuit including said motor and a source of electrical energy, a switch in said circuit, an actuator for said switch, means for releasing a record from said record-support, means associated with said record-releasing means for operating said 70 75

actuator to control the operation of said switch, and independent means for operating said actuator.

7. In a phonograph, in combination, a record-support, a motor for driving said support, a circuit including said motor and a source of electrical energy, a switch in said circuit, an actuator for said switch, means for releasing a record from said record-support, means associated with said record-releasing means for operating said actuator to control the operation of said switch, independent means for operating said actuator, and means associated with said record-releasing means for locking said actuator in a predetermined position.

8. In a phonograph, in combination, a record-support, a motor for driving said support, a circuit including said motor and a source of electrical energy, a switch in said circuit, actuating means for said switch, a record-ejector having "in" and "out" positions relatively to said record-support, and means for locking said actuating means to prevent closing of said switch while said record-ejector stands in its "out" position.

9. In a phonograph, in combination, a mandrel for supporting a record-cylinder, driving means for said mandrel, a record-ejector movable to a certain position by a record-cylinder during the seating of said cylinder upon said mandrel, means for moving said record-ejector away from said certain position to release a cylinder from said mandrel, means responsive to movement of said record-ejector to and from said certain po-

sition for starting and stopping operation of said driving mechanism, and means acting independently of said record-ejector for starting and stopping operation of said driving mechanism.

10. In a phonograph, in combination, a mandrel for supporting a record-cylinder, driving means for said mandrel, a record-ejector movable to a certain position by a record-cylinder during the seating of said cylinder upon said mandrel, means for moving said record-ejector away from said certain position to release a cylinder from said mandrel, means responsive to movement of said record-ejector to and from said certain position for starting and stopping operation of said driving mechanism, means acting independently of said record-ejector for starting and stopping operation of said driving mechanism, and means for preventing operation of said independently acting means to start operation of said driving mechanism when said record-ejector has been moved to release a cylinder from said mandrel.

11. In a phonograph, in combination, a frame, a record mandrel mounted on the frame, a member mounted on the frame adapted to shift a record relatively to said mandrel, an actuating lever, and means operatively connecting said actuating lever with said record shifting member comprising means for moving the said member progressively through increasing increments of travel in response to uniform movement of said actuating lever.

JOHN E. RENHOLDT.
